CONNECTING STRUCTURE

Henry P. Albrecht, Kermitt H. Wilson, and Neil M. Clark, Minneapolis, Minn., assignors to Wilson-Albrecht Co. Inc., Minneapolis, Minn., a corporation of Minnesota

Application December 31, 1949, Serial No. 136,334

5 Claims. (Cl. 189—36)

1

This invention relates to apparatus for detachably joining associated parts of connected structures. While the invention has many possible applications, one particular use in practice thereof is for detachably connecting the load-supporting members or standards of prefabricated, knockdown scaffold structures to cooperating braces or other members thereof.

It is now a common practice to have prefabricated, knockdown supporting structures for scaffolds or platforms which support workers at an elevation. These scaffold-supporting structures generally comprise spaced standards and certain connecting and bracing members. It is desirable to have the various members of these scaffold structures readily detachable so that they can be disassembled for storage and transportation purposes. It is also desirable to have a simple and efficient connecting structure for the various parts by means of which they can be quickly assembled and securely held in assembled relation.

It is an object of this invention to provide a simple and efficient connecting structure including an easily operated locking device or member which will insure that the parts will be securely but detachably held in assembled relation.

It is another object of the invention to provide a connecting structure comprising a load-supporting standard and a member such as a brace connected thereto including a locking member to prevent removal of said connected member or brace, which locking member will be permanently carried on said standard and can be easily and quickly moved to locking or releasing position.

It is more specifically an object of this invention to provide a connecting structure comprising a standard, a pin-like member or stud secured thereto and projecting therefrom, the latter being adapted to extend through an opening in a connected member and to support the same and having a slot extending transversely therethrough adjacent its outer end, together with a locking member having a portion adjacent said standard with a slot therein, said portion being movable transversely of said pin-like member or stud but being prevented from movement longitudinally thereof, said locking member comprising another portion spaced from said first mentioned portion and disposed at the outer side of said connected member adapted to extend through said slot in said pin-like member or stud to prevent removal of said connected member.

These and other objects and advantages of the invention will be fully set forth in the following description made in connection with the accom-

2

panying drawings in which like reference characters refer to similar parts throughout the several views and in which:

Fig. 1 is a perspective view of a scaffold structure of a kind adaptable to practicing of the invention, but in which, view, the lock members of the invention have been omitted in the interest of clarity;

Fig. 2 is a greatly enlarged fragmentary view 10 in side elevation of the connected scaffold structure of Fig. 1, viewed as indicated by line 2—2 of Fig. 1 and associated arrows, but further including a locking member of the invention;

Fig. 3 is a view in side elevation as seen from 15 the right of Fig. 2, but with the brace member removed; and

Fig. 4 is a fragmentary horizontal sectional view taken on line 4—4 of Fig. 2 and looking downwardly, as indicated by the arrows.

20 Referring to the drawings, especially Fig. 1, a knockdown scaffold-supporting device or structure of one type is shown comprising pairs of spaced load-supporting members or standards 10, the same having foot plates 11 at their lower ends. 25 The pairs of standards 10 are connected by cross members 12 at their upper ends, said standards 10 having upwardly extending projections 12a adapted to receive additional supporting standards for a superposed section. The standards 10 of each pair are connected by diagonally extending brace members 13 shown as being connected by a bolt or pin 14 at their crossing points. Other vertical brace members 15 are shown extending from upper cross members 12 respectively to 30 lower cross members 16 extending between and connecting the adjacent standards 10. Other horizontal braces 17 extend between members 15 and one of the standards 10.

35 A preferred form of our improved connecting structure between the standards 10 and the brace members 13 is shown on an enlarged scale in Figs. 2 through 4. Preferably, and as shown, the standards 10 have, secured thereto and projecting substantially perpendicular therefrom, pins or 40 pin-like members or studs 20. While these could be secured to the standards 10 in any suitable manner, in the embodiment of the invention illustrated, the member 20 is shown as set into and welded to said standard, as shown at 10a. 45 Preferably, pin member 20 is provided with a reduced portion 20a adjacent standard 10 and, in the embodiment of the invention illustrated, this is formed by vertical slots 20b at opposite sides of pin member 20. Member 20 also has an elongated aperture or slot 20c extending transversely

therethrough adjacent its outer end. While this aperture or slot could terminate short of said outer end of pin member 20, for convenience of manufacture, it is made to extend through said outer end of member 20 and is closed by a transverse pin 21 extending diametrically of pin 20 through said slot and having its ends riveted at the outer sides of pin 20. Member 20 is adapted to extend through a hole or aperture 13a in one of the brace members 13 and to support said brace member. An inverted U-shaped locking member 24 is provided, and while this might be variously formed, in the embodiment of the invention illustrated, it is shown as formed of a flat plate and as comprising an upper connecting portion 24b, a long inner leg 24a, and a short outer leg 24c spaced from the inner leg to receive the associated end of a brace member 13 therebetween and the inner leg 24a. Preferably, and as illustrated, the short leg 24c of the lock member 24 works slidably through the elongated aperture or slot 20c of pin 20, and the long leg 24a is provided with a longitudinally extended elongated slot or aperture 24f, which is vertically slidably received in the guide slots or channels 20b of pin 20. The outer end walls of the pin slots or channels 20b of pin 20 provide stop portions which define stops which engage the long leg 24a to prevent outward movement on and outward displacement from the pin 20. Member 20 extends through an opening or hole 13a in one end of one of the brace members 13 and supports and anchors said brace member, as shown in Figs. 2 and 4. By reference to Fig. 1, it will be seen that the opposite ends of each of the several brace members 13 are connected to a cooperating load-supporting member or standard 10 by a pin member 20 in the manner shown in Figs. 2 and 4. The said brace member will be disposed adjacent the long leg 24a of lock member 24, as shown best in Figs. 2 and 4. The short outer leg 24c, which extends generally parallel to the long leg 24a, is adapted to be moved into and through the slot 24c, as shown best in Figs. 2 and 4. Preferably, and as shown, the short leg 24c comprises upper and lower sections, respectively indicated by A and B, and a pin-engaging stop shoulder 24d. The inner surfaces of the short leg sections A and B are relatively offset, the space between the upper section A and long leg 24a being sufficient to receive only one brace member 13, and the space between the section B and the long leg 24a being sufficient to receive two of said brace members 13. Member 24 can be moved upwardly to allow two brace members 13 to be applied on pin 20 between the lower section B of leg 24c and the long inner leg 24a. The stop shoulder 24d formed on leg 24c between its sections A and B would then rest upon the outer one of said brace members 13. While short leg 24c may be variously formed, in the embodiment of the invention illustrated, leg 24c is reversely bent at its upper end, as shown in Figs. 2 and 3, and is twisted through substantially ninety degrees (90°). Leg portion 24c is thus disposed in a plane substantially coincidental with or parallel to the axis of pin member 20, while leg 24a is disposed in a plane perpendicular to the pin axis. Leg 24c, at its lower end is provided with an aperture 24e through which a wire or other means such as a resilient cotter pin 25 may be inserted to positively lock the short leg 24c against displacement from the aperture 20c of pin 20.

When one of the brace members 13 is to be connected to or removed from the standard 10, lock

member 24 will be moved to the inoperative position shown in dotted lines in Fig. 2, at which time the end of portion 24c is disposed above pin 20 sufficiently to allow insertion or removal of the brace member over the free end of pin 20. Brace member 13 can now be moved axially or longitudinally on pin member 20 against leg 24a. The lock member 24 can then be allowed to drop downwardly and allow the lower section B of leg 24c to pass into and through the elongated aperture or slot 20c. Member 13 cannot thus be moved off of pin member 20. Leg 24a will be disposed in close proximity to member 13 so that very little transverse movement of member 13 is possible. If desired, a resilient cotter pin, such as 25, a wire or other means may be passed through or snapped into the aperture 24e to prevent member 24 from moving to releasing position. This however is usually unnecessary. With the described structure it will be seen that brace member 13 is now securely held on pin member 20. In erecting the prefabricated, knockdown structure, lock member 24 can be very easily moved to its upper inoperative or release position to permit the placing of brace 13 and member 24 can then be moved or allowed to drop to its operative locking position. The use of a connecting threaded and nutted bolt is thus eliminated. The assembling operators are usually working at an elevation and the bolt or nut is often dropped.

From the above description it will be seen that we have provided a very simple and efficient connecting structure including a locking device, and one which is very efficient and easily operated. The lock member 24 is, as shown, made from a simple plate and can be easily and inexpensively produced. The device has been amply demonstrated in actual practice, found to be very successful and efficient and is being commercially made.

Referring to the drawings, it will be seen that the lower end of slot 24f of the long leg 24a of the lock member 24 is closed to provide a stop C which engages the pin 20 at the extreme of upward movement of pin 24a and prevents upward displacement of lock member 24 from the pin. It will, of course, be appreciated that in preferred practice the several pin members 20 of Fig. 1 will all be correspondingly formed and will be equipped with lock members 24.

It will of course be understood that various changes may be made in the form, details, arrangement and proportions of the parts, without departing from the scope of applicants' invention, which generally stated, consists in a device capable of carrying out the objects above set forth, in the parts and combinations of parts disclosed and defined in the appended claims.

What is claimed is:

1. In a knock-down scaffold structure, a load-supporting standard, a pin carried by and projecting outwardly from the standard, the inner end of the pin being rigid with the standard and the outer end thereof being free, a brace member having an opening adjacent one end receiving said pin, and an inverted U-shaped lock member embracing the brace member and releasably retaining the same on the pin; said inverted U-shaped lock member comprising an upper connecting portion overlying the brace member, a long inner leg disposed adjacent the inner side of the brace member, and a short outer leg generally parallel to the inner leg and disposed adjacent the outer side of the brace member; the legs of the lock member being longitudinally ex-

tended transversely of the pin, as between the pin and each of the legs of the lock member one thereof having an aperture therethrough slidably receiving the other thereof and allowing sliding movements of the lock member transversely of the pin from an operative position wherein both legs of the lock member are in sliding engagement with the pin to an inoperative position wherein the long leg is in sliding engagement with the pin and the short leg is out of sliding engagement with the pin, that portion of the long leg which slidably engages the pin extending sufficiently beyond the plane of the free end of the short leg to remain in sliding engagement with the pin when the free end of the short leg is spaced sufficiently from the pin to allow movement of the brace member longitudinally of the pin to and from its operative position and over the free end of the pin.

2. The structure defined in claim 1 in which the long leg defines a stop portion engageable with the pin at the extreme of movement of the lock member in the direction of its inoperative position to prevent displacement of the lock member from the pin transversely of the latter, and in which the pin defines a stop engageable with the long leg to limit outward movements thereof longitudinally of the pin.

3. In a knock-down scaffold structure, a load-supporting standard, a pin carried by and projecting outwardly from the standard, the inner end of the pin being rigid with the standard and the outer end thereof being free, a brace member having an opening adjacent one end receiving said pin, and an inverted U-shaped lock member embracing the brace member and releasably retaining the same on the pin; said inverted U-shaped lock member comprising an upper connecting portion overlying the brace member, a long inner leg disposed adjacent the inner side of the brace member, and a short outer leg generally parallel to the inner leg and disposed adjacent the outer side of the brace member; the legs of the lock member being longitudinally extended transversely of the pin, said pin having an aperture through its outer end portion slidably receiving the short outer leg of the lock member when the latter is in its operative position, as between the pin and the long leg of the lock member one thereof having an aperture therethrough receiving the other thereof and allowing limited sliding movements of the lock member transversely of the pin from an operative position wherein the short outer leg of the lock member is disposed in its receiving aperture of the pin to an inoperative position wherein the short leg is retracted from the short leg receiving aperture of the pin, that portion of the long leg which slidably engages the pin extending sufficiently beyond the plane of the free end of the short leg to remain in sliding engagement with the pin when the free end of the short leg is spaced sufficiently from the pin to allow movement of the brace member longitudinally of the pin to and from its operative position and over

the free end of the pin, the long leg defining a stop portion engageable with the pin at the extreme of movement of the lock member in the direction of its inoperative position to prevent displacement of the lock member from the pin transversely of the latter, the pin defining a stop portion engageable with the long leg to limit outward movements thereof longitudinally of the pin.

- 5 4. In a knock-down scaffold structure, a load-supporting standard, a pin carried by and projecting outwardly from the standard, the inner end of the pin being rigid with the standard and the outer end thereof being free, a brace member having an opening receiving said pin, and an inverted U-shaped lock member mounted on the pin and embracing the brace member to releasably retain the latter on the pin; said inverted U-shaped lock member comprising an upper 10 connecting portion overlying the brace member, a long inner leg disposed adjacent the inner side of the brace member, and a short outer leg generally parallel to the inner leg and disposed adjacent the outer side of the brace member; the 15 legs of the lock member being longitudinally extended transversely of the pin, said pin having an aperture through its outer end portion for slidably receiving the short outer leg of the lock member when the latter is in its operative position, the long inner leg of the lock member having a longitudinally elongated slot therein slidably 20 receiving the pin, said pin defining a stop shoulder engaging the long leg to retain the same against outward displacement from the pin, said 25 long leg slot extending sufficiently beyond the plane of the free end of the short outer leg to allow bodily upward sliding movements of the lock member to an inoperative position wherein the free end of the short outer leg is displaced 30 from the pin aperture and is sufficiently spaced from the pin to allow sliding movement of the brace member on the pin to and from operative position and over the free end of the pin.

- 35 5. The structure defined in claim 3 wherein the short leg of the lock member comprises upper and lower sections, the inner surface of the latter of which is outwardly offset with respect to the former, the space between the said upper section of the short leg and the long leg being sufficient 40 to receive only one of said brace members and the space between the lower section of the short leg and the long leg being sufficient to receive 45 two of said brace members.
